DESIGN FOR A SCREEN DOOR LATCH

Fay T. Goughnour, Des Moines, Iowa

Application September 8, 1945, Serial No. 121,954

Term of patent 14 years

(Cl. D50—5)

To all whom it may concern:

Be it known that I, Fay T. Goughnour, a citizen of the United States, residing at 3216 Jefferson Avenue, in the city of Des Moines, the county of Polk, and the State of Iowa, have invented a new, original, and ornamental Design for Screen Door Latches, of which the following is a specification, reference being had to the accompanying drawing, forming part thereof.

Figure 1 is a side elevational view of a screen door latch showing my new design, with its lock in closed position;

Figure 2 is a plan view of Figure 1;

Figure 3 is a right end elevational view of Figure 1;

Figure 4 is a left end, elevational view of Figure 1;

Figure 5 is a sectional view taken on the line 5—5 of Figure 2;

Figure 6 is a side elevational view of a screen door latch, showing by new design with its lock in opened position;

Figure 7 is a plan view of Figure 6.

Figure 8 is a right end, elevational view of Figure 6;

Figure 9 is a bottom plan view of Figure 7.

I claim:

The ornamental design for a screen door latch, as shown.

FAY T. GOUGHNOUR.
